CLAIM

We claim the ornamental design for a casement window operator handle and cover, as shown and described.

DESCRIPTION

FIG. 1 is an orthogonal view of a casement window operator handle and cover according to the invention;

FIG. 2 is a front elevation view of the casement window operator handle and cover depicted in FIG. 1;

FIG. 3 is a top plan view of the casement window operator handle and cover depicted in FIG. 1;

FIG. 4 is a right side elevation view of the casement window operator handle and cover depicted in FIG. 1;

FIG. 5 is a left side elevation of the casement window operator handle and cover depicted in FIG. 1; and,

FIG. 6 is a bottom plan view of the casement window operator handle and cover depicted in FIG. 1.

The broken lines shown represent portions of the operator handle that form no part of the claimed design.
